UNITED STATES PATENT OFFICE

ALVA LARENCE OLIPHANT, OF WASHINGTON, KANSAS.

LOADING AND UNLOADING DEVICE.

Application filed December 19, 1921. Serial No. 523,497.

To all whom it may concern:

Be it known that I, ALVA L. OLIPHANT, a citizen of the United States, residing at Washington, in the county of Washington 5 and State of Kansas, have invented a new and useful Loading and Unloading Device, of which the following is a specification.

This invention relates to a new and improved elevating and unloading device, and 10 has for its object to provide a machine which will be of great value in wheat and alfalfa fields, for the machine may be placed on the running gear of any wagon to be operated by the driver from the front seat; and may 15 be raised to the height of ten feet from the ground and dumped in the center of the stack; and may be raised and lowered while going to and returning from the stack; and may also be loaded from either side or 20 turned half way around and loaded from the rear by a hay loader; and may be dumped from either side or both sides at once and will not turn over, since the weight is in the center when one side is being dumped.

Provision is also made, by an improved form of clutching mechanism, whereby the vehicle may be moved from place to place without affecting the operating mechanism 30 which raises and lowers the racks.

Means are also provided for utilizing the machine to carry fruit, vegetables and grain, and for general purposes around the farm.

The invention will be best understood 35 from a consideration of the following detailed description taken in connection with the accompanying drawings forming part of this specification, with the understanding, however, that the invention is not confined 40 to any strict conformity with the showing in the drawings, but may be changed and modified so long as such changes and modifications mark no material departure from the salient features of the invention 45 as expressed in the appended claims.

In the drawings:—

Fig. 1 is a side elevation of the vehicle provided with the automatic elevating and dumping mechanism.

50 Fig. 2 is a rear view of the same, showing the pivoted racks in normal position, and illustrating in dotted lines the dumping position.

Fig. 3 is a plan view of the same.

55 Fig. 4 is a horizontal section of the vehicle, disclosing the operating means con-

nected with the supporting wheels of the vehicle and the means for controlling the clutch mechanism.

Fig. 5 is a side elevation of the vehicle 60 showing a modified form of rack, in tilted position, designed for the purpose of carrying fruit, vegetables or grain.

Fig. 6 is a vertical transverse section of the vehicle, taken along the line 6—6 of 65 Fig. 1.

Fig. 7 is a fragmentary view in horizontal section of the vehicle.

Fig. 8 is a detached view of one of the dumping bodies in tilted position.

Fig. 9 is a side view of one of the sprocket 70 wheels for the rear driving wheel.

Fig. 10 is a perspective detail view of the clutch controlling mechanism.

The elevating and dumping device 75 comprises, generally, a body or main frame provided with axles and wheels, an auxiliary frame rotatably and slidably mounted upon a screw shaft above the main frame, the rotation of the screw shaft causing the elevating or lowering of the auxiliary frame on the main frame, dumping racks pivotally mounted on the auxiliary frame at each side, an operating mechanism for rotating the screw shaft mounted on the main frame and having operative connections with the rear axle, whereby said operating mechanism is driven by the wheels of the vehicle, independent means for manually rotating the screw shaft, an improved form of clutching 80 mechanism for connecting or disconnecting the operating mechanism with the rear axle whereby the auxiliary frame and racks may be elevated or lowered relatively to the main frame, the disconnected operating mechanism permitting the auxiliary frame and the racks pivoted thereon to be elevated or lowered manually, and finally a frame providing a brace for the free end of the screw shaft and having slidable connections with 85 the main frame.

Referring to the drawings, the body comprises a main frame 1, substantially rectangular in form and rigidly mounted on a front transverse beam or bolster 2, and a rear transverse beam or bolster 3. A front axle 4 is rigidly mounted in an arched frame 5 pivotally mounted by kingbolt 6 to the front bolster 2. Front wheels 7 are rotatably mounted on the ends of the front axle. 105 Upon the rear bolster 3 is rigidly mounted an arched frame 8 having depending legs 9

providing bearings for the rotatably mounted rear axle 10. Wheels 11 and 11^a are loosely mounted on the ends of the axle 10.

Mounted centrally of the frame 1 is a vertical screw shaft 12 having a tapered unthreaded lower end 13, seated within a socket 14 supported by a longitudinal rod 15, connected at its opposite ends to the transverse bolsters 2 and 3. A worm gear 16 having 10 an integrally formed depending sleeve 17 is secured upon the screw shaft 12 above the lower end by means of a set screw 18, (Fig. 6).

A U-shaped transverse bracket 19, which 15 is centrally perforated and through which the screw shaft 12 revolves, is connected at its ends to oppositely-disposed U-shaped brackets 20 secured to the frame 1 of the body of the vehicle, said brackets 20 carrying roller bearings 21 upon which the outer periphery of the worm wheel 16 revolves, (Fig. 6). As shown in Fig. 4, oppositely-disposed roller bearings 22 mounted in U-shaped brackets 23 and disposed at right 25 angles to the bearings 21, cooperate with the roller bearings 21 for supporting the outer periphery of the worm gear 16.

A bracket 24, mounted transversely of the frame 1 and in juxtaposition to the worm 30 wheel 16, (Figs. 4 and 7), provides a bearing for a shaft 25 having a worm 26 mounted rigidly therein and engaging the worm wheel 16, and when rotated, adapted to operate the wheel 16 for revolving the screw 35 shaft 12.

Upon the outer end of the shaft 25 is loosely mounted a sprocket 27, engaged by a chain 28, meshing with a sprocket 29, rigidly mounted on the rear axle 10, and 40 connected with the rear traction wheel 11 in such a manner as to provide a lost motion between the wheel and sprocket. This lost motion connection is accomplished by means of a pin 30 secured to and passed 45 through a spoke of the rear wheel 11, and engaging at its end with one of the openings in the body of the sprocket wheel 29. The opening in the sprocket wheel is of a considerably larger diameter than the pin 30 50 in order to permit a certain amount of play between the traction wheel 11 and the sprocket wheel 29, so that as the vehicle is pulled forwardly or moved rearwardly, the pin will not immediately engage the sprocket 55 wheel to drive it, but the wheel will be capable of a partial rotation before the pin will engage the peripheral edge of the opening in the sprocket wheel and cause the two to be rotated simultaneously, (see Figs. 7 60 and 9).

As shown in Figs. 6 and 7, the sprocket 27 is provided with an upstanding pin 31, which is adapted to be engaged by a laterally-extending pin 32, on a slidably mounted sleeve 33, the said sleeve being adapted to

be moved towards the sprocket 27, so that the pins 31 and 32 will engage each other. As the traction wheel 11 is rotated, the pin 30 will engage the sprocket wheel 29, causing the same to rotate, and through the chain 28 cause the sprocket 27 to be rotated, and because of the engagement of the two pins just described, the sleeve 33 which is keyed upon the shaft 27, will cause the shaft 25 to be rotated; likewise, the worm 26, the worm wheel 16 and the screw shaft 12. The manner of shifting the sleeve 33 will be described later.

Near the end of the shaft 25, which is opposite to the end upon which the sprocket 27 is mounted, is another sprocket 34 rigidly mounted upon the shaft 25 and adapted to be rotated always when said shaft is rotated. The sprocket 34 is engaged by a chain 35, which in turn engages another sprocket 36 rigidly mounted on a countershaft 37, the countershaft having bearings in an inverted U-shaped bracket 38 mounted upon the frame 1, (Figs. 4 and 6). Slidably mounted on the end of the countershaft is a gear 39 having a laterally projecting pin 40 adapted to engage an outstanding pin 41 mounted on the countershaft 37, when the gear 39 is shifted inwardly towards the lug 41 in a manner which will be presently described. 95 When the pins 40 and 41 are engaged, the gear 39 and shaft 37 will be rotated simultaneously.

A gear 42 rigidly mounted on the axle 10 is always in engagement with the gear 39, 100 and has an upstanding lug 43 on its hub adapted to engage a pin or lug 44 securely mounted on the other traction wheel 11^a, so that as the wheel 11 is revolved when the vehicle is pulled forwardly, the pin 44 will 105 be revolved to a point where it will engage the pin 43, and thereby cause the gear 42 to be rotated and likewise the gear 39, (Fig. 7). When the lugs 40 and 41 are in engagement, the rotation of the gear 39 will cause rotation 110 of shaft 37, sprocket 36, sprocket 34 through driving chain 35, worm shaft 25, worm wheel 16 and screw shaft 12, but in an opposite direction to the direction of rotation caused by the traction wheel 11.

The frame 45 and likewise the pivoted racks 46 and 47 are elevated when the shaft 12 is caused to be rotated through the sprocket 27 by means of its connection with the rear wheel 11, and these parts are lowered when the shaft 12 is rotated through the connections by means of the sprocket 34, chain 35, the gear 42, and the rear wheel 11^a. 115

The clutching mechanism, which selectively causes the wheel 11 or the wheel 11^a to 120 operate the shaft 12 in opposite directions for elevating or lowering the racks and the auxiliary frame 45 will now be described.

A longitudinal shaft 48 is slidably and rotatably mounted in the bearings 49 and 50 125 130

at the forward part of the vehicle body or main frame. Springs 51 and 52 are adapted to normally maintain the shaft 48 inwardly in the position shown in Fig. 4. A sleeve 55 is slidably keyed to the shaft 48, and a spring 53, connected at one end to the bearing 49 and at the other end to the sleeve 55, is so tensioned that it normally maintains arm 54, which is secured to the forward end of the 10 shaft, in upright position. Upon the inner end of the shaft 48, is rigidly mounted a collar 56, having a depending tongue 57, engaging an opening in a link 58, (Fig. 7), and adapted to be oscillated when the arm 54 on 15 the other end of the shaft is manually oscillated. The arm 54 has an upstanding vertical position and is normally in the same plane with the tongue 57 when in such position.

20 A socket 59, mounted upon the upper end of the arm 54, is provided with a perforation, through which is inserted the angular rod 60, held in position within the perforation of the socket 59 by means of a set screw.

25 Rigidly mounted upon the outer free end of the rod 60 is a dog 61, having inner beveled faces which neatly fit between a pair of triangular-shaped teeth 62 of the toothed wheel 63, rotatably mounted at 64 upon the front 30 of the vehicle and projecting slightly beyond the same, in order that the dog 61 may be engaged between a pair of said teeth.

As the arm 54 is oscillated from right to left, or vice versa, the shaft 48 will be pulled 35 outwardly since the dog 61 will always be maintained in engagement between a pair of the teeth, and be shifted laterally from side to side as the toothed wheel 63 is rotated. The toothed wheel carries the dog 61 in an 40 arc of a circle towards and away from the front end of the vehicle. The wheel 63 may be operated in any approved manner, as by a crank arm secured to the wheel and located in position to be operated by the driver of the 45 vehicle.

The link 58 has pivotally mounted thereon the inner ends of links 65, 66, (Figs. 4 and 7). The outer end of the link 66 is pivotally mounted upon the end of a lever 67, the 50 other end of which is pivotally mounted at 71 on a bracket secured to the U-shaped bracket 38, and provided with a fork 68 engaging the slidable sleeve 33. The fork through the lever 67 is adapted to shift said sleeve on the shaft 25. The link 65 is connected to a lever 69, the other end of which is provided with a fork 70, engaging a reduced portion on one end of the gear 39, for shifting the gear along the shaft 37 in order 55 to throw the pins 40 and 41 into engagement.

It will be seen that when the arm 54 is shifted from the center of the front end of the vehicle to the right, by the rotation of the wheel 63, the shaft 48 will 60 be moved inwardly by reason of the teeth 65 of the wheel 63 moving inwardly in an arc of a circle towards the front end of the vehicle, the dog 61 following the teeth, and permitting the shaft 48 to slide inwardly, and also rotating the shaft 48 in such a manner that the tongue or lug 57 is moved towards the left, shifting the links 65 and 66 towards the left side of the frame 1, and carrying the front end of the lever 67 outwardly and away from the side of the frame 1. 70

Since the other end of the lever 67 is pivoted at 71, upon a bracket located upon the U-shaped bracket 58, the fork 68 which engages the sleeve 33 will also be moved outwardly and carry said sleeve outwardly and toward the end of the shaft 25, and cause the pin 32 to engage the pin 31 on the sprocket 27. If the vehicle is moving forwardly, the wheel 11 will be revolved together with sprockets 29, and 27, by reason of the chain 28, and 80 cause the sleeve 33 to be rotated. Since the sleeve 33 is keyed upon the shaft 25, the shaft 25 will be rotated, as will the worm wheel 16 and the screw shaft 12. The auxiliary frame 45 and the racks 46 and 47 will thus 85 be elevated.

As the links 65 and 66 are moved to the left of the frame, as shown in Fig. 4, the outer end of the link 65 is likewise moved toward the left of the vehicle, and inwardly 90 towards the frame, carrying the front end of the lever 69 inwardly, while the rear end which carries the fork 70 will be moved outwardly, since the lever 69 is pivoted at 72 on a bracket depending below the frame 1, 95 and thereby moving the gear 39 outwardly toward the end of the shaft 37, and carrying the pin 40 away from the pin 41 to disengage the gear 39 from its connection with the shaft 37. 100

The shaft 25 being rotated as stated above, the sprocket 34 will be rotated, and through the chain 35 will rotate the sprocket 36 and the countershaft 37, but by reason of the fact that the gear 39 has been disengaged from its 105 connection with the shaft 37, gears 39 and 42 will not be operated by the shaft 37. The gear 39 will nevertheless revolve idly on said shaft 37 because wheel 11^a is revolving and rotating gear 42. 110

By turning the arm 54 to its vertical central position, lever 67 will be moved sufficiently to withdraw the sleeve 33 inwardly from the end of the shaft 35, causing disengagement of the pins 32 and 31, while pin 40 on gear 39 and pin 41 on the counter-shaft 37 will not have been moved sufficiently inward toward each other to be engaged. Traction wheels 11 and 11^a may thus 115 be revolved by the forward movement of the vehicle without causing a rotation of the shaft 25. 120

If the arm 54 be moved to the left, the tongue or lug 57 will be moved towards the right, carrying the links 65 and 66 likewise 130

1. towards the right, oscillating the levers 67 and 69 on their pivots. The forked end of the lever 69 will be moved inwardly, carrying the gear 39 sufficiently inward and away 5 from the end of the shaft 37, so that pin 40 will engage the pin 41. The simultaneous oscillation of the shaft 67 on its pivotal point 71, will cause the sleeve 33 to be moved farther inwardly from the end of the shaft 10 25, so that pins 31 and 32 will be farther removed from each other to maintain the sprocket 27 and the shaft 25 in disengaged relation to each other. In this position, the sprocket 27 will rotate idly on the shaft 25, 15 but the sprocket 34 which is secured to the shaft 25 will be rotated through the chain 35, sprocket 36, shaft 37, gear 39, by reason of the engagement of the pins 40 and 41, gear 42 in mesh with the gear 39, and lastly, 20 through the wheel 11^a by reason of its connection with the gear 42, through the pins 43 and 44.

It may be stated here that in either case where the wheels 11 and 11^a are rotated by 25 traction, that the axle 10 will always be rotated by both wheels simultaneously through gear 42 being connected to the axle and also to the wheel 11^a. The sprocket 29 connects the axle 10 with the wheel 11, whereby wheel 30 11 rotates the axle.

Slidably mounted upon the screw shaft 12 is an internally threaded sleeve 73, secured to a beam 74 arranged longitudinally of the frame 45, having secured upon its 35 outer ends transverse members 75, upon which are pivotally mounted, at 76 and 77, racks or dumping bodies 46 and 47, respectively. The racks 46 and 47, shown in Figs. 1 to 4, inclusive, and Fig. 6, are designed for 40 carrying hay or fodder, while the rack or dumping body 78, shown in Fig. 5, is for the purpose of carrying grain, fruits or vegetables.

The racks disclosed in Figs. 1 to 4, inclusive, and Fig. 6, have a base portion 79, end members 80, and adjacent inner side members 81 formed of a framework provided with spaced vertical bars. Through the spaces between these bars are adapted to operate bars 82 forming a sort of rake, which bars are secured at their upper ends in a longitudinal bar 81^a pivoted on each of the dumping bodies. To one end of each longitudinal bar is mounted a handle 83 for oscillating the prongs or bars 82 of the rake for moving the hay or fodder or other contents outwardly towards the sides of each dumping body to force the material from the same. As Fig. 3 shows, one handle 83 is 55 located at the front end of one of the rakes and the other handle is placed at the rear end.

The dumping bodies or racks 46 and 47 are pivotally mounted upon the auxiliary frame 45, and are each partly maintained in 60

position by means of a crank arm 85 which is pivotally mounted in brackets connected to the cross beam 74. Each arm 85 is adapted to be engaged in a socket 86, secured to the bottom of each of the dumping bodies 46 70 and 47. The shaft upon which the crank arm 85 is formed extends longitudinally beyond the end of each dumping body, and is provided with a crank arm 87, adapted to be held in place by a perforated clip 88, through 75 which the free end of the arm 87 is inserted, the clip being slidably mounted upon the transverse bar 75, (Figs. 2 and 3). This mechanism is in duplicate, one for each dumping body being located at opposite ends 80 and in reverse positions. When the clip is moved sufficiently along the bars 75 to be entirely removed from engagement with the end of the rod 87, the rod 87 may be tilted upwardly, carrying with it the operating arm 85, and causing the dumping body to be tilted outwardly and in dumping position for discharging the hay or fodder from the racks.

The screw shaft 12 being mounted vertically and centrally of the main body of the vehicle is therefore located between the inner sides of the dumping bodies, and the bodies may be locked in normal position by means of the locking members 89, pivoted 90 to a collar 89^a of sleeve 90, which is loosely mounted upon the upper free end of the screw shaft 12. These locking members are to be manually operated.

Mounted upon the upper end of the sleeve 90, in lugs projecting in opposite directions upon opposite sides of the sleeve, are a pair of brace rods 91 extending forwardly towards the front of the vehicle, and secured to the hollow downwardly-depending rods 92, which are telescopically mounted upon vertical posts 93, firmly secured to the front end of the main frame 1 of the vehicle. Rigidly secured to the sleeve 90 and projecting rearwardly from said sleeve is a single 110 brace rod 94, rigidly secured to a downwardly-depending hollow rod 95, telescopically mounted upon an upstanding post 96 secured upon the rear end of the frame 1. The two bodies or racks are arranged close together 115 at their meeting sides and their top rails 82^a are cut out at the center to embrace the sleeve 90.

The sleeve 90 being loose upon the shaft 12 is adapted to be moved in a vertical position along the screw shaft, when the upper rails 82^a of the bodies contact with the collar 89^a, causing the brace rods 91 and 94 to be moved upwardly and thereby carrying the hollow rods 92 and 95 slidably mounted upon the posts 93 and 96. The purpose of this construction is to provide for supporting the racks or bodies in the variously adjusted positions. By this construction the bodies may be raised to a height of ten feet 125 130

above the ground, and the braces will follow the adjustment of the bodies.

The posts 93 and 96 cooperate with the hollow rods 92 and 95, and the horizontally-extending rods 91 and 94, to form a bracing means for supporting the upper free end of the screw shaft 12.

Projecting outwardly from the ends of the auxiliary frame 45 are lugs upon which are pivotally mounted U-shaped clips 97 and 98. The front U-shaped clip 97 is adapted to engage a lug 97^a upon the front part of the framework 1, while the rear U-shaped clip 98 is adapted to engage the rod 95 and maintain the frame 45 and the racks 46 and 47 in a position longitudinally of the body, which is the normal position of the racks.

The racks 46 and 47, as illustrated in Figs. 1 to 4, inclusive, and Fig. 6, are not only differently constructed for the purposes of holding different kinds of materials, but the gate construction as well as operation of the preferred form and the modified form are somewhat different. Referring more particularly to Figs. 1 and 2, the pivoted racks 46 and 47 each have pivoted gates 99, mounted upon the ends of arcuate brackets 100, which are secured to the ends of the racks. A rod 101 is secured in the outer free end of each top beam 102 of the gate, and extends rearwardly and downwardly along the outside end of the rack and has a crank portion 103 bent at right angles to the rod 101 and passed through a perforation in the bracket 100 and secured in the lower beam or base of the gate. Springs 104 are fastened at 105 to each end of the rack, extend outwardly along the ends of the rack, and have their outer free ends slidably mounted upon the rod 101. This construction is duplicated at each end of the rack. The inclination of the spring 104 from the horizontal is such that whether the gate is closed or open, the spring will always be maintained at the same angle relative to the horizontal. This is accomplished by means of the sliding connection between the spring 104 and the rod 101, and because of the right angular bent portion of the rod, as shown at 103. When the gate is lowered or tilted outwardly from the rack, as shown in Fig. 8, the eye 105 of the spring will always be maintained in the same position, since the rod 101 and bent portion 103 change their positions relatively to the end 105 of the spring in such a manner that the rod 101 moves through the eye without changing the inclination of the spring 104. Chains 106 are adapted to be connected between the ends of the rack and the top of the gate to limit the outward throw of the gate.

As disclosed by Fig. 5, the rack 78 is adapted for the purpose of containing

grains, fruits or vegetables, and therefore instead of the sides being formed of an open framework constructed of spaced bars, all portions of it are solid. This rack 78 is provided with a side extension 107 which forms the contracted mouth or outlet for the rack. Pivots mounted upon the sides 108 of the rack 78 are gates 109, which are adapted to be moved to or away from each other, and are maintained in outward position by means of the flanges 110, formed on the side edges of the spout 107. The chain 111 is adapted to cooperate with the flanges 110 to prevent the gates from being forced open by the weight of the fruit or vegetables contained in the rack 78. If necessary, the chain 111 may be drawn up taut and bring the two outer edges of the gates together and close the opening.

As has been stated above, the clutching mechanism is adapted to disengage the sprocket 27 from the shaft 25, and likewise the gear 39 from its engagement with the shaft 37, thereby permitting the vehicle to be drawn forwardly, with the wheels 11 and 11^a revolving, without rotating the worm shaft 25 and causing the screw shaft 12 to be rotated. If, at any time, it be desired to elevate or lower the auxiliary frame 45 which carries the racks 46, 47 or 78, the same may be done without the use of the power for moving the vehicle, or there may be times when it is not feasible to lower or elevate the racks by means of the power developed from the traction wheels of the moving vehicle. At such a time, the hand crank 112, which is connected to the worm shaft 25, may be operated in the direction indicated by the arrow in Fig. 1, for rotating the screw shaft 12 to elevate the racks and the auxiliary frame. In order to lower the racks of the frame, the crank arm 112 may be operated in a reverse direction, but before the screw shaft may be rotated by means of the crank arm 112, the clutch must be thrown in such a position that the arm 54 will be vertically positioned, when the wheels 11 and 11^a will be disconnected from the mechanism which operates the worm shaft 25. In this position of disengagement, the worm shaft may be readily rotated by the crank arm 112 in either direction for elevating or lowering the racks. The crank arm is removable, as shown in Fig. 6, and is only used when the occasion requires.

The operation of the device is as follows:—While I have described the operation of the different parts in their cooperative engagement with each other for producing certain results, nevertheless I will summarize in a general manner the operation of elevating or lowering the racks by means of the construction described.

In drawing the vehicle from one place to

another, the arm 54 of the clutching mechanism is normally placed in a vertical position and held in such a manner by means of the engagement with the dog 61 between 5 a pair of teeth 62 of the toothed wheel 63. In this position, the levers 67 and 69 will have positioned the sleeve 33 away from the end of the shaft 25 so that the lugs 31 and 32 are out of engagement, while the 10 lever 69 will move the gear 39 outwardly and toward the end of the countershaft 37, so that the pins 40 and 41 will be disengaged. It will be seen that when the wheels 11 and 11^a are revolved by traction, they 15 will drive the axle 10 and likewise gears 42 and 39, and sprockets 29 and 27, without causing rotation of the shaft 37. Therefore, the sprockets 34 and 36 will remain idle, as likewise will the shaft 25. The 20 sprocket 29 will be rotated to drive the chain 28 and the sprocket 27, but since the sprocket 27 is loosely mounted on shaft 25 and not in engagement with the sleeve 33, sprocket 27 will revolve idly on the shaft 25. 25 without causing rotation of the shaft 25. In this position of the clutching mechanism, the vehicle may be drawn forwardly without affecting rotation of the shaft 25 or the screw shaft 12.

30 If it be desired to elevate the racks 46 and 47, after the racks have been loaded with hay or fodder, at a short distance before reaching the destination where the material is to be dumped, and towards which 35 the vehicle is being drawn, the clutch is thrown towards the right in front of the vehicle, when the lever 67 will be moved outwardly beyond the side of the frame 1, carrying with it sleeves 33 and throwing 40 pins 31 and 32 into engagement with each other, so that as the sprocket wheel 27 is rotated by the wheel 11 and the axle 10, the worm shaft 25 likewise causes the worm, wheel 16 and the screw shaft 12 to be rotated and thereby elevate the racks. If the 45 place of destination has not been reached before the racks have been elevated to the proper height, the clutch may again be thrown into neutral; that is, with the operating arm 54 of the clutching mechanism being placed in its vertical position in the 50 center of the front end of the vehicle and held by the toothed wheel 63.

The vehicle having reached its place of 55 destination and the racks 46 and 47 having been elevated to their proper height, one of the clips or locking members 88, which are slidably mounted upon the auxiliary frame 45, is moved outwardly towards the end of 60 the bar 75 and disengaged from the operating rod 87. The operating rod 87 may be lifted, and by reason of the arm 85 which is connected to the arm 87 and likewise to the pivoted rack 46 by means of a socket

86, the rack will be tilted as the arm 87 is 65 raised. The weight of the material, such as hay or fodder, in the racks will be sufficient to open the gates 99 when the rack has been tilted upon its pivot 76, and the fodder or hay will drop out of the racks 70 into the barn or onto the stack. If it be found that the hay or fodder collects at the inside of the rack, the arm 83 may be oscillated, causing the rake 82 to force all such material forwardly and down the inclined bottom of the rack. 75

After one side has been emptied of its material, the arm 87 may be returned to its position and locked upon the clip 88, thereby returning the dumping body or rack to 80 its normal horizontal position. The racks and auxiliary frame 45 may be rotated upon the shaft 12 after the clips 97 and 98 have been removed from their engagement respectively with the lug 97^a and the slidably 85 member 95 of the brace member. After the rack, which has not been emptied, has been turned toward the barn, the clips 97 and 98 will be dropped back in their locking position, when the rack may be tilted 90 in the same manner as described for the first rack.

The rack 78, shown in Fig. 5, which is a modification, is tilted in the same manner as are the racks 46 and 47, and the auxiliary 95 frame 45 is adapted to be elevated and lowered by the rotation of the shaft 12. The auxiliary frame may be rotated upon the shaft 12 as an axis for bringing either of the racks 78 upon one side of the vehicle and 100 for the purpose of emptying both racks on one side.

When it is desired to lower the auxiliary frame 45 and the racks 46 and 47, the operating arm 54 of the clutch is thrown over to 105 the left, when the outer end of the lever 69 will be thrown outwardly from the side of the frame 1 and rotated upon its pivot 72, so that the inner or forked end 70 of said lever is thrown inwardly, and the gear 39 is shifted inwardly and away from the end of the shaft 37, so that the lugs 40 and 41 will be in engagement with each other and the gear 39 will operate the shaft 37; likewise, the sprockets 36 and 34, worm shaft 25, 110 worm gear 16 and the screw shaft 12. At the same time, the lever 67 will also be oscillated and moved inwardly towards the frame 1, causing the sleeve 33 to be moved inwardly from the end of the shaft 25 and disengaging the pins 31 and 32, when the sprocket 27 will rotate idly on the shaft 25. When the shaft 12 is rotated, through the gear 42, countershaft 37, sprockets 36 and 34, the movement will be in a direction which is reverse to the direction indicated by the arrow in Fig. 1, and therefore will cause the racks 46 and 47 to be lowered as the ve- 115 120 125

hicle is driven forwardly and away from the barn or its former dumping place. When the racks have been sufficiently lowered, the internal sleeve 73 will rest upon the spring

5 113, and the operating arm 54 of the clutching mechanism will be again shifted into its normal neutral vertical position upon the front end of the vehicle frame.

As the auxiliary frame 45, carrying the 10 racks 46 and 47, is elevated by means of the rotating screw shaft 12, the bracing means which supports the upper free end of the screw shaft 12 will be carried upwardly by reason of the inner adjacent sides of the 15 racks engaging the slideable sleeve 90 of said bracing means, and causing the said sleeve to be moved upwardly on the shaft 12, and by reason of the outwardly-extending arms 91 and 94, the telescoping rods 92 and 95, 20 which are respectively slidably mounted on the front post 93 and the rear post 96, will be carried upwardly with the sleeve.

The clips 97 and 98 not only lock the auxiliary frame 45 and the racks 46 and 47 25 from rotary movement on the shaft 12, but the clip 98 has slideable engagement with the telescoping rod 95 so that no matter how high the racks are raised, they are held from such movement. By disconnecting the clip 30 98 from the rod 85, the racks may be turned as desired.

For lowering the empty racks, the crank handle 112 may be operated in a direction which is the reverse of the direction indicated by the arrow in Fig. 1, after the operating arm 54 has been placed in its normal neutral vertical position on the front end of the vehicle frame.

In filling the racks 46 and 47, in which 40 fodder or hay is packed, for removal from one part of the farm to another, the auxiliary frame 45 is rotated upon the shaft 12 as an axis so that the racks 46 and 47 are located transversely of the body and are positioned in this manner, since it is more convenient for loading the same. After the racks have been loaded they may be returned to their normal longitudinal position along the frame and locked in position 45 by means of the clips 97 and 98. It is possible to load the racks from either side, or turned half way around and load from the rear of the vehicle, or they may be dumped from either side separately, or both at once, 50 and the machine will not turn over.

What is claimed is:—

1. A device of the character described, comprising a wheeled supporting frame, a screw shaft mounted upon said frame, an auxiliary frame provided with a rack having a vertical and rotary movement on the shaft, which extends above the auxiliary frame, and means for rotating said screw shaft for imparting a vertical movement to

the auxiliary frame and the rack, and an 65 overhead means above the rack connected to the upper end of the screw shaft for bracing the same.

2. A device of the character described, comprising a wheeled supporting frame, a 70 screw shaft mounted upon said frame substantially in the center thereof, an auxiliary frame having an internally threaded sleeve engaging with said screw shaft and a vertical and rotary movement on said shaft, 75 means for rotating said screw shaft for imparting a vertical movement to the auxiliary frame, and racks pivotally mounted at the outer sides of the said auxiliary frame on opposite sides of said shaft, and movable 80 outwardly from said shaft in dumping, and when in normal closed position embracing said shaft.

3. A device of the character described, comprising a wheeled supporting frame, a 85 vertically-disposed screw shaft mounted centrally upon said frame, an auxiliary frame having an internally threaded sleeve engaging with said screw shaft and movable both vertically and horizontally thereon, racks 90 carried by said auxiliary frame on opposite sides of the longitudinal center of the wheeled frame, said racks being pivotally mounted to dump at each side, and means mounted on the screw shaft engaging the 95 inner side of the racks to hold the same from dumping.

4. A device of the character described, comprising a wheeled supporting frame, a vertical screw shaft mounted upon said 100 frame, an auxiliary frame mounted centrally on said shaft and carrying a rack and having a vertical movement on the shaft, means extending from the wheeled frame outside the rack for bracing the upper end 105 of the shaft, a worm wheel mounted at the lower end of the screw shaft, a worm engaging the worm wheel, and means for rotating the worm wheel through one of the wheels of the supporting frame.

5. A device of the character described, comprising a wheeled supporting frame, a vertical screw shaft mounted upon said frame, an auxiliary frame mounted centrally on said shaft and provided with a rack 115 having a vertical movement on said shaft, means extending from the wheeled frame outside the rack for embracing the upper end of the shaft, an axle rotatably mounted on the supporting frame, wheels mounted 120 on the axle, a sprocket rigidly mounted upon the axle adapted to be rotated by one of the wheels, a worm shaft on the supporting frame provided with a worm wheel, a worm mounted on the screw shaft and meshing 125 with the worm, a sprocket loosely mounted on the worm shaft connected by a chain to the sprocket on the axle, and a clutch mech-

- anism for connecting the loosely mounted sprocket on the worm shaft with said shaft.
6. A device of the character described, comprising a supporting frame mounted upon traction wheels, an axle rotatably mounted on the supporting frame, a vertical screw shaft mounted upon said frame, an auxiliary frame provided with a rack and having a vertical movement on the shaft, said shaft being located centrally of the auxiliary frame and extending above the same, and an overhead means above the rack connected to the upper end of the screw shaft for bracing the same, a worm shaft mounted on the supporting frame and geared to rotate the screw shaft, a gear and sprocket rigidly mounted on the axle and adapted to be operatively connected with the worm shaft, the sprocket and gear having separate connections with the traction wheels, and means for connecting the sprocket with the worm shaft while simultaneously disconnecting the gear with said shaft.
7. A device of the character described comprising a wheeled axle, a supporting frame mounted thereon, a screw shaft mounted upon said frame, gearing connecting the shaft with the axle and including a lost motion connection, an auxiliary frame provided with a rack and having a vertical movement on the shaft, a worm shaft mounted on the supporting frame and geared to rotate the screw shaft, a gear and a sprocket rigidly mounted on the axle and adapted to be operatively connected with the worm shaft, the sprocket and gear having separate connections with the traction wheels, means for connecting the gear with the worm shaft while simultaneously disconnecting the sprocket with said shaft, said means being adapted to simultaneously disconnect both the sprocket and the gear from said shaft.
8. A device of the character described comprising a wheeled axle, a supporting frame mounted thereon, a screw shaft mounted upon said frame, gearing connecting the shaft with the axle and including a lost motion connection, an auxiliary frame provided with a rack and having a vertical movement on said shaft, a worm shaft mounted on the supporting frame and geared to rotate the screw shaft in one of two directions, a gear and sprocket rigidly mounted on the axle and adapted to be operatively connected with the worm shaft, the gear and sprocket each having separate connections with a traction wheel, means for connecting one of said sprockets with the worm shaft while simultaneously disconnecting the other sprocket with the worm shaft, said sprocket when connected with the worm shaft being adapted to rotate the screw shaft for elevating the auxiliary frame when the traction wheels are rotated, and said screw shaft adapted to be operated in a reverse direction for lowering the auxiliary frame when said gear wheel on the axle is connected to the worm shaft and operated by the traction wheels.
9. A device of the character described, comprising a wheeled supporting frame, axles rotatably mounted on the frame, traction wheels loosely mounted on the axle, a gear and a sprocket rigidly mounted on the axle, said wheels having separate connections with the sprocket and gear, a screw shaft mounted on the frame, an auxiliary frame provided with a rack and having a vertical movement on the shaft, a countershaft mounted on the supporting frame, a worm shaft rotatably mounted on the frame geared to operate the screw shaft and having operative connections with the countershaft, a pinion slidably mounted on the countershaft and engaging the gear on the axle, a sprocket loosely mounted on the worm shaft having connections with the sprocket on the axle, a clutch mechanism adapted to cause the sprocket on the worm shaft to engage the shaft and rotate the same when the traction wheels are rotated and to simultaneously disconnect the pinion from driving relation with the countershaft.
10. A device of the character described, comprising a wheeled supporting frame, axles rotatably mounted on the frame, traction wheels loosely mounted on the axle, a gear and a sprocket rigidly mounted on the axle, said wheels having separate connections with the sprocket and gear, a screw shaft mounted on the frame, an auxiliary frame provided with a rack and having a vertical movement on the shaft, a countershaft mounted on the supporting frame, a worm shaft rotatably mounted on the frame adapted to operate the screw shaft for elevating or lowering the auxiliary frame and having connections with the countershaft, a pinion slidably mounted on the countershaft and engaging the gear on the axle, a sprocket loosely mounted on the worm shaft having connections with the sprocket on the axle, a clutch mechanism adapted to simultaneously cause the sprocket on the worm shaft to engage the shaft and rotate the same when the wheels are rotated and to disconnect the pinion from driving relation with the countershaft, said clutch mechanism adapted to simultaneously disconnect the loosely mounted sprocket and the countershaft from driving relation with the worm shaft, and manual means for rotating the worm shaft in either direction for causing rotation of the screw shaft when said sprocket and countershaft are disconnected.
11. A device of the character described, comprising a supporting frame, a vertical screw shaft rotatably mounted centrally on said frame, an auxiliary frame provided

with a rack having a vertical movement on said shaft adapted to be elevated or lowered by rotation of said shaft, means for rotating said shaft, posts mounted upon the ends of 5 the supporting frame, and a bracing means for the upper free end of the screw shaft slidably mounted on said posts.

12. A device of the character described, comprising a supporting frame, a vertical 10 screw shaft mounted centrally on said frame, means for rotating said shaft, an auxiliary frame provided with a rack and having vertical movement on said shaft so as to be elevated or lowered by the rotation of said 15 shaft, posts mounted upon the supporting frame at the front and rear, and a bracing means for the upper end of the screw shaft slidably mounted on said posts and also 20 slidably connected to the end of the screw shaft.

13. A device of the character described, comprising a supporting frame, a vertical screw shaft mounted centrally on said frame, means for rotating said shaft, an auxiliary 25 frame having a rack and connected to said shaft so as to be elevated or lowered by rotation of said shaft, posts mounted upon the ends of the supporting frame, bracing means between the upper end of the screw shaft and 30 said posts, said bracing means being elevated with the shaft when the latter is rotated.

14. A device of the character described, comprising a supporting frame, a vertical screw shaft mounted centrally on said frame, 35 means for rotating said shaft, an auxiliary frame having a rack and connected to said shaft so as to be elevated and lowered by the rotation of the latter, a sleeve loosely mounted at the top of said shaft, posts arising 40 from the supporting frame, and bracing means between the movable sleeve and said posts having a fixed connection with the sleeve and an extensible connection with the posts, whereby when the rack is elevated it 45 contacts with the sleeve and raises the latter and thereby elevates the bracing means in harmony therewith.

15. A device of the character described, comprising a supporting frame, a vertical 50 shaft mounted centrally on said frame, means for rotating said shaft, an auxiliary frame having a rack and connected to said shaft so as to be elevated and lowered by the rotation of the latter, and bracing means 55 having connection with the top of said shaft and raised and lowered in harmony with the raising and lowering of the rack.

16. A device of the character described, comprising a supporting frame, a vertical 60 shaft mounted centrally on said frame, an auxiliary frame having a vertical and a rotary movement on said shaft and provided with pivotally mounted racks, a sleeve movably mounted at the top on said shaft, and 65 means connected with the sleeve for engag-

ing and locking the pivoted racks in position on the auxiliary frame.

17. A device of the character described, comprising a supporting frame, a vertical shaft mounted on said frame, an auxiliary 70 frame having a vertical and a rotary movement on said shaft and provided with pivotally mounted racks arranged side by side and on opposite sides of the shaft, a sleeve movably mounted at the top of said shaft, 75 and depending rocking members carried by said sleeve adapted to engage the inner sides of the racks for locking the same in position on the auxiliary frame.

18. A device of the character described, comprising a supporting frame, a vertical shaft mounted centrally on said frame, an auxiliary frame having both a vertical and a rotary movement on said shaft, means for rotating said shaft for elevating and lowering 80 the auxiliary frame, racks pivotally mounted on the auxiliary frame, means locked upon the auxiliary frame for maintaining the pivoted racks in position on the frame, said means when released adapted to 85 be operated for dumping said racks.

19. A device of the character described, comprising a supporting frame, a vertical shaft mounted centrally on said frame, an auxiliary frame having both a vertical and 90 a rotary movement on said shaft, means for rotating said shaft for elevating and lowering the auxiliary frame, racks pivotally mounted on the auxiliary frame and adapted to swing outwardly, and separate means 95 mounted upon the auxiliary frame and connected with the racks for tilting the same, said means being located at opposite ends of the auxiliary frame and adapted to be locked in position.

20. A device of the character described, comprising a supporting frame, a vertical shaft mounted centrally on said frame, an auxiliary frame having both a vertical and a rotary movement on said shaft, means for rotating said shaft for elevating and lowering 100 the auxiliary frame, racks pivotally mounted on the auxiliary frame and tilttable outwardly at opposite sides, a shaft mounted at each end of the auxiliary frame, said 105 shafts each having a crank arm adapted to engage with a socket provided in the bottom of each rack, and means at the end of the shaft outside the racks for locking the same.

21. A device of the character described, comprising a supporting frame, a shaft mounted centrally on said frame, an auxiliary frame having a vertical movement on 110 said shaft, means for rotating said shaft for elevating and lowering the auxiliary frame, racks pivotally mounted on the auxiliary frame and tilttable outwardly at opposite sides, the inner side of each rack being 115 formed of spaced bars, and a rake mounted 120

along the inner side of each rack and having its teeth movable through the spaces between the bars of the racks.

22. A device of the character described, comprising a supporting frame, a vertical shaft mounted centrally on said frame, an auxiliary frame having vertical and rotary movement on said shaft, means for rotating the shaft for elevating and lowering the auxiliary frame, racks pivotally mounted on the auxiliary frame and tiltable outwardly, and means pivotally mounted at the inner side of each rack and adapted when operated to force materials carried by said rack 10 out of the rack when the same has been tilted to dumping position.

23. A device of the character described, comprising a supporting frame, a vertically movable pivoted rack mounted on the frame 20 and tiltable outwardly, one side of the rack being formed with spaced bars, a rake mounted along the same side of the rack as said bars and having its teeth movable in the spaces between the bars of the rack, and 25 manually operated means for tilting the rake.

24. A device of the character described, comprising a supporting frame, a vertical shaft mounted on said frame, an auxiliary 30 frame having both a vertical and a rotary movement on said shaft and provided with a rack, means for rotating said shaft to raise and lower the auxiliary frame, and pivoted clips mounted on extensions of the auxiliary 35 frame to engage fixed parts of the stationary frame to hold the auxiliary frame from rotation.

25. In a device of the character described, the combination of a pivoted rack having a 40 pivoted gate at one side, a pair of rods each having a crank portion and arranged at opposite ends of the rack and connected to the pivoted gate, and a spring fastened to each end of the rack and slidably freely upon the 45 rod.

26. A device of the character described, comprising a supporting frame, a vertical

shaft mounted centrally on said frame, means for rotating the shaft, an auxiliary frame elevated or lowered by the rotary 50 movement of said shaft and provided with a rack, said auxiliary frame adapted to be manually rotated on the shaft, posts mounted upon the supporting frame, a bracing means for the upper end of the screw shaft 55 slidably mounted on said posts, and means pivotally mounted on the auxiliary frame and adapted to engage the bracing means for maintaining the auxiliary frame in position longitudinally of the supporting 60 frame.

27. A device of the character described, comprising a supporting frame, a screw shaft mounted centrally of said frame, pivoted racks having connections with the screw 65 shaft for supporting and locking the racks against tilting, said racks being raised and lowered by the rotation of the screw shaft, and means for rotating said shaft.

28. A device of the character described, comprising a supporting frame provided with axles and wheels, a screw shaft mounted vertically on said frame, a rack having connection with said shaft, means connected with an axle and a wheel for causing rotation of the screw shaft in one direction, a second means connected with an axle and a wheel to cause the reverse motion of the screw shaft, and means adapted to be operated from the front of the supporting 70 frame for connecting either of said means with an axle or simultaneously disconnecting both the said means, including a longitudinal shaft slidably and rotatably mounted at the forward end of the frame and having an upstanding arm, a dog carried by said arm, a toothed wheel adapted to be engaged by said dog, and link mechanism operated by the slidable movement of said longitudinal shaft. 75

In testimony that I claim the foregoing as my own, I have hereto affixed my signature.

ALVA LARENCE OLIPHANT.
